UNITED STATES PATENT OFFICE

DONALD L. HADLEY, OF MANSFIELD, OHIO, ASSIGNOR TO WESTINGHOUSE ELECTRIC
AND MANUFACTURING COMPANY, A CORPORATION OF PENNSYLVANIA

DESIGN FOR A LATCH

Application filed December 7, 1929. Serial No. 33,686. Term of patent 14 years.

To all whom it may concern:

Be it known that I, DONALD L. HADLEY, a citizen of the United States, residing at Mansfield, in the county of Richland and State of Ohio, have invented a new, original, and ornamental Design for Latches, of which the following is a specification, reference being had to the accompanying drawings, constituting a part hereof.

Figure 1 is a plan view, and

Fig. 2 is an elevational view of a latch showing my new design.

I claim:

The ornamental design for a latch as shown.

In testimony whereof, I have hereunto subscribed my name this 27 day of November, 1929.

DONALD L. HADLEY.
